IMMERSION HEATER

John D. Morgan, South Orange, N. J., assignor to
 Power Patents Company, Hillside, N. J., a corporation of Maine

Application May 25, 1937, Serial No. 144,604

6 Claims. (Cl. 219—41)

The present invention relates to electrical heating devices and more particularly to those devices that are immersed in liquids for the purpose of heating the same.

5 Heretofore many immersion type electrical heaters have been developed that employ the use of a heating coil wound upon a mica or porcelain core and then enclosed in a metal casing or jacket. Heaters constructed in that manner have been 10 found objectionable because in many cases the metal container in which the heating core is encased cannot be brought into direct contact with certain liquids that are to be heated.

Another objection to the use of such heaters is 15 that the heating elements easily yield to the corroding effect of the liquid where the element is in direct contact with the liquid for any appreciable length of time.

Another objection to the heaters in use at the 20 present time is that the heating elements are embedded in dielectric binders that possess a low heat conductivity coefficient, with the result that it takes an appreciable length of time in which to heat a given amount of liquid.

25 An object of the present invention is to provide an immersion heater with a metallic heating element embedded in a dielectric material of high heat conductivity.

Another object of the invention is to provide 30 an immersion heater in which the dielectric material in which the heating element is embedded is not in direct contact with the liquid to be heated, thus reducing all possibility of corrosion of the parts by the liquid.

35 Another object of the invention is to provide an immersion heater with a dielectric embedding material and a glass envelope which surrounds the dielectric of approximately the same coefficient of thermal expansion so that the glass envelope will not shatter or crack upon a sudden 40 rise in temperature of the heating element.

Another object of the present invention is to provide a heater that has no metal parts in contact with the liquid to be heated.

45 With the above and other objects and features in view the invention comprises the improved immersion heater hereinafter described and more particularly defined by the accompanying claims.

50 The heater herein described is one that has particular application as an immersion heater of the type used by doctors and dentists for sterilizing the instruments used in their practice, but it is to be understood that the invention is not limited to that type of heater, as the heater can be

made into any shape or size to fit any particular need or application.

The various features of the invention are illustrated in the accompanying drawing in which:

Fig. 1 is a view of the heater immersed in a 5 receptacle of water or other liquid to be heated.

Fig. 2 is a cross sectional view of the heater; and

Fig. 3 is a longitudinal sectional view of a 10 modified form of heater permanently mounted in a heating receptacle.

Referring more particularly to the drawing, Fig. 1 shows the preferred type of heater 10 submerged in a container 12 that is partly filled with water or other liquid. Resistor 14 which serves 15 to heat the fluid, is embedded in dielectric carrier 16. The preferred refractory dielectric carrier is made up of a mixture of substantially 60 parts by weight of ferrosilicon, 40 parts of milled grain zircon and 6 parts of phosphoric acid. This refractory has the desirable property of being able to be hand molded and shaped and can be readily bonded to the glass casing in which it is enclosed. The zircon-ferrosilicon refractory described above has a thermal conductivity better than that of 20 steel. Because of the close contact between the glass casing and the refractory embedding material, the loss in heat transfer is negligible. The refractory in which the heating element is embedded has a coefficient of thermal expansion 25 approximately .0000025.

Dielectric carrier 16 is encased in an envelope 18 that is preferably composed of a non-porous material such as glass or fused quartz having a coefficient of thermal expansion approximately 30 the same as that of the dielectric material 16. The casing therefore is preferably composed of Pyrex type glass, that is a glass composed of a mixture of the oxides of boron and silicon, having a coefficient of thermal expansion of approximately 40 .0000032. The dielectric carrier 16 and casing 18 may be physically bonded so that the resistor 14 is in very close contact heat conductivity relationship with the outer shell, being separated merely by the layer of refractory in which 45 it is embedded. It can be readily understood that the resistor element should be positioned as close to the outer shell as possible so that a very effective transfer of heat to the outer shell and liquid can be accomplished.

50 Lead wires 20, 20' are conducted from the dielectric carrier into a glass extension tube 21 that is physically bonded to the top of the heater at a point where the lead wires can be assembled for introduction into the tube. Within the tubing 55

21, the lead wires are enclosed in a flexible cable
22 that is provided with electrical terminals (not
shown) adapted to make proper electrical connec-
tions to a source of current in a manner well-
known to the art.

5 Fig. 3 shows an immersion heater embodying
the basic features of my invention showing an-
other type of construction. In this adaptation
of the invention, the heater is mounted in the
10 side of the vessel or receptacle containing the
liquid to be heated. The receptacle has a threaded
opening on any one side into which the
threaded nipple 24 can be screwed. Bushing 28
15 that is slotted to receive the lead wires is set
within the nipple 24. The outer shell 18 of the
heater can be rigidly fixed into the nipple by
cementing or other known means. In order to
assure a continuous flow of convection currents
20 through and around the heater, casing 18 is
perforated with one or as many openings 25 as
desired to allow liquid to complete a continuous
flow through the openings.

An immersion heater employing all of the fea-
tures hereinabove disclosed has been made and
25 put into use. The resistor employed was #22
gauge wire. Pyrex glass having a thickness of $\frac{1}{2}$
inch was used as the casing for the embedding
material. The heater was equipped with a 1000
30 watt element and connected to a 115 volt line.
Upon test it was found that it required but five
minutes to bring one quart of water to boiling
temperature. As shown in Fig. 1, the heater was
35 so constructed that both ends are open to facilitate
the rapid heating of the water. Convection
currents of the heated water from the bottom of
the heater to and through the open top will cause
additional cold water to be drawn through the
40 heater. In this manner a continuous flow of
liquid through and around the tube is effected.
By the use of the glass tube leading from the
edge of the heater to above the surface of the
water at no time is there any metal or electrical
45 lead off wires in direct contact with the water
or liquid to be heated. This feature of my in-
vention enables one to use the heater in liquid
that ordinarily might be chemically affected by
contact with metal or rubber covered wires. For
example, the heater can be used for heating liquid
50 foods of all kinds. It is also ideally adapted for
sterilization purposes where utmost cleanliness of
the boiling solution is of prime importance.

While I have described one particular modi-
fication of the invention, it is to be understood
55 that the heater can be made in any desirable
shape or size.

The length, bore and outside diameter of the
heater can be made variable dependent upon
the use to which the heater will be subjected.

The resistor used as the heating element may
60 also depend upon the use to which the heater will
be applied. Platinum or tungsten elements can
be used where high temperatures are required.
Carbon or nickel chromium alloys can be used
when low temperature heating is needed.

While I have described an immersion heater
that is made up of Pyrex type glass or fused
quartz as the material to be used for the outer
covering, I do not so limit the invention. I have
also found it suitable to utilize a metal casing
5 which can be used where the utmost cleanliness
of the liquid is not of the first importance pro-
vided the metal has the proper coefficient of ex-
pansion. One type of metal that can be used as a
casing is a metal such as "invar", that is, a metal
10 alloy composed of two thirds iron and one third
nickel and small traces of carbon. This alloy
was found to have a coefficient of thermal ex-
pansion only slightly higher than that of the
dielectric carrier in the temperature range used
15 for heating liquids.

Having thus described the invention, what is
claimed as new is:

1. An electric immersion heater comprising a
resistor embedded in a dielectric carrier of high
heat thermal conductivity composed of a bonded
20 mixture of zircon, ferrosilicon and phosphoric
acid, said dielectric carrier being enclosed in and
bonded to a casing of desired shape that has a
coefficient of thermal expansion approximately
25 the same as that of the dielectric.

2. An electric immersion heater comprising a
resistor embedded in a dielectric carrier of high
heat thermal conductivity composed of a bonded
30 mixture of zircon, ferrosilicon and phosphoric
acid, said dielectric carrier being enclosed in and
bonded to a glass envelope of desired shape that
has a coefficient of thermal expansion approxi-
mately the same as that of the dielectric.

3. An immersion heater as described in claim 1
35 in which the dielectric is composed of a mix-
ture of 60 parts of ferrosilicon by weight, 40 parts
of zircon, and 6 parts of H_3PO_4 .

4. An immersion heater as described in claim 2
40 in which the glass comprising the envelope is
composed of a mixture of the oxides of boron
and silicon adapted to give a coefficient of ex-
pansion substantially equal to that of the dielec-
tric.

5. An electric immersion heater comprising a
resistor embedded in a dielectric carrier of high
heat thermal conductivity composed of forty
45 parts by weight of milled grain zircon, sixty
parts by weight of ferrosilicon, and six parts of
phosphoric acid bonded to produce a refractory
having a coefficient of thermal expansion of ap-
proximately .0000025, said dielectric carrier being
50 enclosed in a casing of desired shape that has a
coefficient of thermal expansion approximately
the same as that of the dielectric.

6. An electric immersion heater comprising a
resistor embedded in a dielectric carrier of high
heat thermal conductivity composed of a bonded
55 mixture of zircon, ferrosilicon and phosphoric
acid, said dielectric carrier being enclosed in a
casing of desired shape that has a coefficient
of thermal expansion approximately the same as
that of the dielectric.

JOHN D. MORGAN.
